UNITED STATES PATENT OFFICE.

HARRY HERMAN, OF PASADENA, CALIFORNIA.

IRONING-BOARD.

1,245,280.

Specification of Letters Patent.

Patented Nov. 6, 1917.

Application filed February 1, 1917. Serial No. 145,885.

To all whom it may concern:

Be it known that I, HARRY HERMAN, a citizen of the United States, residing at Pasadena, in the county of Los Angeles 5 and State of California, have invented new and useful Improvements in Ironing-Boards, of which the following is a specification.

The object of this invention is to provide 10 a rigid flat working table; and provide a steam heating and steam distributing sleeve pressing ironing board which will swing downwardly and rest firmly upon the front of a rigid table with its face up; the steam 15 pipe connections forming a base for supporting the pressing board upon the rigid table and said pipe connections forming a swinging support connected at the rear of the table for carrying the whole pressing 20 board apparatus upwardly out of the way; so that the working table will be clear for flat work; and provide a valve for the steam distributing feature and operate the valve from a stationary foot treadle.

25 The invention is illustrated, by way of example, in the accompanying drawings in which:

Figure 1 is a view in side elevation illustrating the completely assembled board with 30 parts broken away to more clearly and conveniently disclose its construction.

Fig. 2 is a view in plan illustrating the apparatus disclosed in Fig. 1 and particularly illustrates the formation of the ironing board and the steam control mechanism.

Referring more particularly to the drawings, 10 indicates a suitable rigid flat working table supported by pedestals 11 and 12. Secured to the rear end of the table and 40 extending upwardly and rearwardly therefrom is a mounting bracket 13. This bracket is adapted to support a lateral and horizontal steam pipe 14. This pipe is connected with a cut-off valve 15 which controls 45 the flow of steam thereto from a supply pipe 16. The supply pipe 16 extends vertically and downwardly and is suitably connected to a source of steam supply not shown in the drawings. Threaded upon the oppo- 50 site end of the lateral pipe 14 is a pipe 17 which establishes communication with a longitudinally extending pipe 18. This pipe passes above the table and extends approxi- 55 mately the length thereof. Interposed at a point along its length is a regulating cut-

off valve 19 which directly controls the passage of steam to an ironing board 20.

The swinging ironing board, as here shown, is formed with a base plate 21, upon which is mounted a separator plate 22. This 60 plate is formed to provide a steam chest 23 between it and the base plate 21. Mounted over the plate 22 is the top plate 24. This plate is adapted to be covered with a fabric 25 and to provide a surface upon which 65 clothes may be pressed. Referring particularly to Fig. 1 of the drawings it will be seen that this is formed with downwardly extending side flanges which connect with the top of the plate. It will also be noted 70 throughout the length and width of the top portions of the plate a series of perforations 26 are formed and adapted to communicate with a steam space 27 between the top plate 24 and the separator 22. This space is supplied with steam through a vertical pipe 28 which communicates directly with the pipe 18 and is controlled by the regulating valve 19. The steam chest 23, between the base 75 and separator plate is constantly supplied 80 with steam through a pipe 29, connecting with other pipes 30 and 31, a series of which may be used and which in turn communicate with the pipe 18, prior to the mounting of 85 the regulating valve thereon.

As a means for preventing the accumulation of condensed steam within the steam chest 23 and the compartment 27, two drain pipes are provided: an open drain pipe 32 and a valve control drain pipe 33. These 90 two pipes connect with a flexible tube 35 which permits the water of condensation to be readily carried away. The pipe 32 extends horizontally and connects to the vertically extending pipe 28. The pipe 33 is 95 obliquely inclined and connects by means of a series of pipe fittings to the chest 23, it being understood that various branches may be made to this pipe in order to properly and thoroughly drain the chest. This pipe 100 is opened and closed by means of a valve 33'.

In order to permit ready control of the steam delivered to the compartment 27 and from thence to the top plate 24, a lever arm 19' is secured to the stem of the valve 19 105 and normally holds the valve in a closed position by means of a tension spring 36. An actuating cable 37 is secured to this arm and led rearwardly over a pulley 38 mounted at the rear end of the table. From this point 110

the cable is carried the full length of the table and passes over the pulley 39 which causes the end of the cable to hang downwardly and engage the lever of a foot

- 5 treadle 40 suitably mounted upon a pivot pin 41 adjacent the pedestal 11 of the table. This arrangement of the cables is provided in order to permit the steam fittings and the ironing board to be swung upwardly and 10 away from the table in the direction of the arrow —a—, this being accomplished by permitting the elbow 17 to turn upon the lateral pipe 14 and effect a pivotal movement of the apparatus. The ironing board 15 is connected at the rear of the table and rests upon the front of the table for use and when the ironing board is swung upwardly out of use the entire table is available for other purposes.
- 20 When this pressing apparatus is to be used the cut-off valve 15 is first opened and will allow steam to pass through the pipe 18 to pipes 30 and 31 and from thence through pipe 29 to the steam chest beneath the separator plate. This will insure that the entire ironing board, which is of metal, will be thoroughly heated, after which the regulating valve 19 will be opened by a downward movement of the foot treadle 40 and 25 will cause steam to pass into the compartment 27 and from thence through the perforations 26 in the top board 24. The condensed steam which accumulates in the compartment 27 will be constantly drawn off 30 through the drain pipe 32 and the condensed steam forming in the chest 23 may be drawn off as required by manipulation of the valve 33'. The garments may thereafter be 35 pressed upon this board by means of mechanical pressing machines or by hand irons. When it is desired to use the rigid ironing board the pressing board with its steam pipes may be swung out of the way, as previously described and disclosed in 40 Fig. 1 of the drawings.

I am aware that steam ironing boards have been made and I do not desire to claim such construction broadly; but I am not aware

that a steam ironing board has been constructed and mounted to swing downwardly and rest upon a table for use and swing upwardly clear of the table out of use.

I claim:

1. In an ironing board, a suitable support, a bracket extending upwardly and rearwardly from the suitable support, a horizontal laterally extending steam pipe mounted in the bracket, a supply pipe connected to one end of this steam pipe through a cut-off valve, an elbow connected to the other end of the lateral pipe, a pipe connected to the elbow and extending longitudinally above the suitable support and to near the front end thereof, there being a regulating valve in the longitudinal pipe, a vertical pipe connected to the forward end of the longitudinal pipe, and a steam heated ironing board mounted upon the vertical pipe; said longitudinal pipe being long enough to bring the ironing board to the front part of the suitable support and the suitable support serving to support the pipes to support the steam heated ironing board when in a horizontal position and said elbow forming a joint to allow the steam heated ironing board to 75 swing upwardly from the suitable support.

2. In an ironing board, a suitable support, a steam pipe mounted to swing up and down upon the suitable support, a regulating valve in the steam pipe, a steam heated ironing board fixed upon the forward end of the steam pipe, a spring for holding the regulating valve closed, a cord connected to the regulating valve and extending backwardly over a pulley mounted at the rear end of the suitable support and then forwardly over a second pulley at the front of the suitable support and downwardly, and a foot treadle connected to the lower end of the cord; so that the operator in front of the suitable support working upon the ironing board may control the regulating valve.

In testimony whereof I have signed my name to this specification.

HARRY HERMAN.
